AIR PUMP.

Application filed October 23, 1923. Serial No. 670,248.

My invention relates to air pumps of the type adapted to be put into wells for the purpose of forcing liquid from the well to a place of delivery above the surface, and it 5 has among its salient objects: to provide a device adapted to be placed down in a well to any desired depth to receive the liquid to be lifted, with an air-pressure operated valve or gate to control the inlet of the liquid 10 thereto, and with air pressure for forcing said liquid from said device through a discharge pipe to the surface, said air pressure being controlled at the surface; to provide in a device of the character referred to, air-operated valve members located down in the 15 well and controlled from the surface through the medium of compressed air; to provide a simple and practical, self-contained device of the character referred to and to which air 20 pipes and discharge pipe for the liquid can be attached as it is placed down in the well, thus providing a device which can be removed bodily from the well for adjustments or repairs; and, in general, to provide an 25 improved means and method for forcing water, oil, or other liquid from a well by means of air under pressure.

In order to explain my invention, I have 30 illustrated one practical embodiment thereof on the accompanying sheet of drawings, in which,—

Figure 1 is a vertical sectional view showing a well casing with my device in place therein, all shown in section and with parts 35 broken out to reduce the length of the view;

Figure 2 is a cross sectional view taken on line 2—2 of Fig. 1;

Figure 3 is a cross sectional view taken on line 3—3 of Fig. 1;

Figure 4 is a cross sectional view taken on line 4—4 of Fig. 1;

Figure 5 is a vertical sectional view taken on line 5—5 of Fig. 3;

Figure 6 is a vertical sectional view taken on line 6—6 of Fig. 3;

Figure 7 is a vertical sectional view taken on line 7—7 of Fig. 3; and

Figure 8 is a perspective view of an air moved valve member.

Referring now in detail to the drawings, the invention as here embodied for descriptive purposes, comprises a well casing, 10, in which is placed a cylindrical member 11, closed at its bottom and provided with inlet

openings 11' through its side, said cylinder having secured in its upper end three cylindrical members, as 12, 13 and 14, fitted closely together flatwise, substantially as shown, the middle member 13 having a central bore, as 13^a, which extends partly into the member 12, as at 12^a, and partly into the member 14, as at 14^a, constituting a cylinder within which is mounted a piston, 15, having a piston rod, 16, attached to a cylindrical gate, 17, by means of a spider member 18. Said 65 gate is also provided with inlet openings, 17^a, adapted to register with the inlet openings 11' when said cylindrical gate is in one position, as shown in the drawings, and to close said inlet openings 11' when said cylindrical gate or valve is moved. An outlet or discharge pipe, 19, is provided which is screwed into an opening 12^b in the member 12, said pipe extending down into the cylindrical member 11 and cylindrical gate 17, 70 through the spider 18, as shown, and being provided with an inlet check valve, 20, at its lower end, substantially as shown. The members 12, 13 and 15, also have holes therethrough, as 12^b, 13^b and 14^b, forming a continuation of said pipe, 19, with a pipe extension 19^a screwed into the opening 14^b in the upper member 14, as illustrated, said discharge pipe, it being understood, can be extended to any desired place of discharge. 85

An air supply pipe, 21, is extended down into said well and connected at its lower end to an opening 14^c in the member 14, and a second air supply pipe, 22, is extended down into said well and connected at its lower end 90 to an opening, 14^d, back of the opening, 14^b, in Fig. 1, but seen in Fig. 7. These air supply pipes 21 and 22 are connected by means of a valve structure, 23, with valve, 24, therein, with a single air supply pipe, 25, from 95 any suitable source of air supply. The valve 24, can be operated in any desired manner, for alternately connecting the pipes 21 and 22 with the one supply pipe 25, as will be clear from the showing. I have shown no 100 special means of operating the valve 24, as this can be mechanically operated, or otherwise to alternately supply air under pressure through the pipes 21 and 22.

The block member 13, has formed therein 105 a semi-circular valve chamber 13^c, in which is slidably mounted a correspondingly shaped valve member 26, having at one end

and at the lower side thereof, an extension 26^a, to cover and uncover the hole 12^c when moved to one end of the valve chamber 13^c, said valve chamber being slightly enlarged 5 or cut out around the bottom thereof to provide space to receive a lip flange 26^b, around the lower face of the valve member 26. It will be understood that the hole 14^a, the valve chamber 13^c and the hole 12^c, together 10 form a continuation passageway from the air supply pipe 22, for the supply of air under pressure through said blocks 12, 13 and 14, to the cylinder 11, when said valve member 26 is moved to the right. This 15 will be understood from Fig. 7, the valve 26 being in section. The opposite ends of said valve member 26 are cut away slightly, as at 26^c, to provide sufficient space around the end of said valve member when moved 20 to its stop position to admit air for the initial movement of said valve member from one end of the valve chamber to the other end thereof. The valve member 26 is moved from one end to the other by air pressure 25 admitted first to one end of the chamber 13^c and then to the other end thereof, from the pipes 21 and 22.

Said valve member 26 has a vertical port, 26^a, therethrough, with an extension, as 26^b, 30 Fig. 8, to one side thereof in the top face of the valve member, and with a similar extension, 26^c, to one side thereof in the inner face of said valve member, for a purpose hereinafter again referred to. When in the 35 position indicated in Figs. 2, 3 and 6, said vertical port 26^a in the valve member 26 registers with a port, 14^c, in the head block 14, and also, at its lower end, with a port, 12^c, in head block 12, while the lower extension, 26^c, communicates through passageways 13^c and 12^c, with the lower end of the piston cylinder, at 12^a, under the piston 15, as seen in Fig. 6. When said valve member 26 is moved to the right, said vertical port 40 26^a, at its upper end, continues to be in communication with the port 14^c, in the head block 14, by means of its extension 26^b. It will be seen that when in the position shown in Fig. 6, exhaust from the piston cylinder 45 and also from the receiving cylinder 11, is open at the same time.

Referring again to Figs. 3 and 7, another port 13^c is formed in the side of said head block 13, at the side of the valve chamber 50 13^c. This port is closed when the valve member 26 is in its left hand position, as shown, but is adapted to be opened by the initial movement of said valve member 26 to the right, as will be understood from 55 Fig. 3. This initial movement of said valve member 26, however, first closes a similar port 13^a, Figs. 3 and 5, which leads to the upper end of the piston cylinder through port 14^a in head block 14. These ports 13^a 60 and 14^a admitted the air to the piston cylinder 13^a and 14^a and force the piston 15 downwardly to open the cylindrical gate 17, as shown in Fig. 1, when the valve member 26 was moved to its shown position.

The use and operation of my invention 70 may be briefly stated as follows:

When the valve 24, which controls the admission of air under pressure from the pipe 25 was turned to the position shown and air was admitted to pipe 21, the valve member 26, at that time to the right hand end of the valve chamber 13^c, was moved to its shown position, the air entering in the cut-out portion 26^c sufficiently to initially start said valve member to the left and then forcing 75 it all the way to the opposite end of said valve chamber 13^c. This opened ports 13^a, from the valve chamber, 13^c, and 14^a, admitting air under pressure from supply pipe 21, to the top of the piston cylinder, at 14^a, 80 and forcing said piston downwardly and opening the cylindrical gate 17 for the admission of liquid to the cylinder 11. It also opened the ports 14^a, 26^a, 26^c and 12^a, and 12^c, as shown in Fig. 6, to permit exhaust 85 from the lower end of the piston cylinder 12^a, as said piston 15 moved downwardly, and to permit exhaust from the main cylinder 11, as the liquid rises therein 90 through the ports 11' and 17^a, from the well casing 10. Thus air from supply pipe 21, operates only to move the valve member 26 to the left, whereby exhaust is established from the lower end of the piston cylinder and from the receiving cylinder, and air is 95 supplied to the top of the piston cylinder to move the piston 15 downwardly and open the main inlets 11' and 17. Now when the valve 24, is turned to direct air from pipe 25 to pipe 22, the following things are 100 accomplished in the order named: initial movement of valve member 26 to the right; closing of port 13^a; opening of port 13^c to admit air to the lower end of the piston cylinder, as 12^a, Fig. 7, to raise the piston 105 110 and close the main cylindrical gate 17; moving the port extension 26^c in the valve member 26 to register with the port 13^c, Fig. 3, giving exhaust from the upper end of the piston cylinder, 14^a, Fig. 5; said exhaust being through the vertical port 26^a in valve 115 26, its extension 26^b, and the port 14^c in head block 14. The final movement of the valve member 26, moves its foot extension 26^a from over opening 12^c and thus admits 120 the full supply of air from pipe 22, through passageway 14^a, valve chamber 13^c (left hand end thereof), passageway 12^c, to the top of the receiving cylinder 11, and forcing 125 the contents therefrom through the check valve 20 and out through the discharge pipe 19 and 19^a, as will be understood from Fig. 1.

Thus with a very simple and practical apparatus, I am able with air under pres- 130

sure to manipulate the control valves and control the admission of liquid to a receiving cylinder down in a well, and to force it therefrom to the surface, and while I have shown but one embodiment of the invention, I am aware that changes in details can be made without departing from the spirit thereof, and I do not limit the invention to this showing, except as I may be limited by 10 the hereto appended claims.

I claim:

1. In a pump for a well casing in combination, a receiving member placed down in said well casing with valve controlled inlet 15 port, a valve therein for controlling said port, cylinder and piston means therein for moving said valve to open and closed positions, an air supply pipe for supplying air to operate said piston and said valve, an 20 air supply pipe for supplying air to said receiving member, a discharge pipe leading from said receiving member, a check valve therein to permit outflow therefrom, and an air-operated valve mechanism for controlling 25 the admission of air under pressure from said air supply pipes to said cylinder and piston and to said receiving member.

2. In a pump for a well casing in combination, a receiving member placed down in 30 said well casing with valve controlled inlet port thereto, a valve therein for controlling said port, air-operated means in said receiving member for moving said valve, a supply of air under pressure, means for admitting air under pressure to said receiving 35 member, a discharge pipe leading from said receiving member to the surface, a check valve therein, air-operated means in said receiving member for controlling the admission 40 of air to said receiving member, and means at the surface for controlling said air-operated means for moving said valve and for controlling admission of air to said receiving member.

3. In a pump for a well casing in combination, a receiving cylinder placed down in said well casing with inlet openings through 50 its side, a cylindrical gate therein for closing said inlet openings, air operated means in said cylinder for moving said cylindrical gate, a source of supply of air under pressure, supply pipes for carrying said air under pressure to said receiving cylinder, a discharge pipe leading from said receiving 55 cylinder to the surface, a check valve in said discharge pipe, and an air operated valve member in said receiving cylinder for controlling the air-operated means for moving said cylindrical gate and the inlet of air 60 to said receiving member, said air operated valve member being moved by the admission of air under pressure alternately to said supply pipes.

4. In an apparatus of the character referred to, in combination, a receiving mem-

ber to be placed down in a well, closed at both ends, two air supply pipes extended thereto, a source of air under pressure, means for alternately admitting said air to said supply pipes, a discharge pipe from 70 said receiving member to the surface, said receiving member having inlet openings through its side, a valve member therein controlling said inlet openings, cylinder and piston means in the upper part of said 75 receiving member connected with said valve member for moving the same to alternately open and close said inlet openings, and means whereby air through said air supply pipes operates said piston to move said valve 80 member.

5. In a pump for a well in combination, a container placed down in said well to receive liquid therefrom, an inlet valve therein for controlling the inflow of liquid 85 to said container, operating means in said container, connected to said valve, and controlled at the surface for opening and closing said valve, a discharge pipe from said container to the surface, an air supply pipe to said container, means for supplying air under pressure to said container to force liquid therefrom through said discharge pipe, and a valve mechanism in said container for controlling inlet and exhaust ports 90 from said container, said valve mechanism being operated by air pressure from the surface, substantially as referred to.

6. In a pump for a well in combination, a container placed down in said well, said container having inlet openings to receive liquid from said well, a gate for controlling said inlet openings, pneumatic means in said container for operating said gate, a discharge pipe from said container to the surface, a check valve in said discharge pipe, air supply pipes from the surface to said container, means for supplying air under pressure alternately to said supply pipes, and a valve mechanism in said container, 100 adapted to be moved by air pressure from said supply pipes alternately in opposite directions, said valve mechanism being designed to control the admission of air to the pneumatic means for operating said gate and the admission of air to said container to force liquid therefrom, substantially 105 as described.

7. In a pump for a well in combination, a container placed down in said well, pneumatically operated mechanism in said container for intermittently admitting liquid thereto from said well, a discharge pipe from said container to the surface, an air supply pipe from the surface to said container for supplying air to force liquid out through said discharge pipe, pneumatically operated valve mechanism in said container to control the admission of said air to said container and to the mechanism for admit- 115 120 125 130

- ting liquid to said container, and means at the surface for controlling the supply of air under pressure to said container and its air operated mechanisms.
5. 8. In a pump for a well in combination, a container placed down in said well, a discharge pipe from said container to the surface, said container having a gate controlled inlet opening to admit liquid thereto, a cylinder with piston therein in said container, said piston being connected to open and close said gate, two air supply pipes from the surface to said container, means for controlling the admission of air under pressure alternately to said supply pipes, and a valve mechanism operated alternately by the air from said supply pipes for controlling the admission of air to said cylinder for operating said piston and gate, and for admitting air to said container to force liquid therefrom through said discharge pipe.
9. In a pump for a well in combination, a container placed down in said well and having inlet openings through its side, a gate therein to open and close said openings, a discharge pipe from said container to the surface, a check valve in said pipe, a cylinder with piston therein in said container and connected for operating said gate, two air supply pipes from the surface to said container, means for alternately admitting air under pressure to said supply pipes, a valve mechanism in said container for alternately admitting air from said supply pipes to the top and bottom of said cylinder for operating said gate, said valve mechanism being adapted to control the admission of air to said container for forcing liquid therefrom through said discharge pipe, and means whereby the alternate supply of air through said two air supply pipes alternately moves said valve mechanism from one position to another to operate said mechanisms for receiving liquid from said well and discharging it through said discharge pipe.
10. In a mechanism of the character referred to, in combination, a container adapted to be placed down into a well of liquid, gate-controlled inlet through the side of said container, a cylinder with piston therein forming a part of said container in said well for operating said gate, air supply pipes from the surface for supplying air under pressure to said cylinder and said container, a discharge pipe from said container to the surface for discharging liquid from said container, a control valve in said discharge pipe, a shiftable valve mechanism forming a part of said container, in said well, to control the admission of air under pressure from said supply pipes to said cylinder and to said container, said shiftable valve mechanism being operable by air from said supply pipes, whereby the alternate supply of air through said pipes operates said mechanisms relative to each other to admit liquid to said container and to force it out through said discharge pipe, substantially as described.
11. In an air pump, in combination with a container to be placed down in a well, and having inlet openings, a valve therein for controlling said inlet openings, a cylinder and piston forming a part of said container and having its piston connected to said valve for moving the same to open and close said inlet openings, a shiftable valve member in said container for controlling inlet and exhaust ports from said cylinder to move said piston, air supply pipes from the surface to said container and to said shiftable valve member, whereby air alternately from said supply pipes operates to shift said valve and move said piston and said valve for controlling the inlet openings to said container, and a discharge pipe from said container to the surface.
12. In an apparatus of the character referred to, a cylindrical container having its lower end closed and having a head structure provided with a cylinder and piston therein, said container having inlet openings in its side, a gate valve therein connected with said piston and adapted to be moved thereby to open and close said inlet openings, air supply pipes from the surface to said container, a discharge pipe from said container to the surface, a valve member associated with the cylinder and piston in said head structure and adapted to be moved automatically by air pressure to control the admission of air to said cylinder for moving said piston, and means for controlling the supply of air from the surface through said air supply pipes, substantially as described.
- Signed at Los Angeles, Los Angeles County, California, this 9th day of October, 1923.

JAMES W. LOY.
